COMPRESSION TESTING DEVICE FOR THIN MATERIALS

Wiley P. Montgomery, Washington, D. C., assignor to United Aircraft Corporation, East Hartford, Conn., a corporation of Delaware

Application October 22, 1942, Serial No. 462,916

6 Claims. (Cl. 265—12)

This invention relates generally to materials testing apparatus and more particularly to a device for making compression tests of relatively thin sheet specimens.

It has heretofore been difficult to make a compression test of a relatively thin specimen such as sheet material because of the lateral instability of the specimen under a compression load. To overcome this difficulty, it has been customary to employ the so-called "pack" method wherein a large number of thin sheets are cemented together in laminated form to provide a composite specimen of relatively large cross-sectional area that has inherent lateral stability under a compression load. However, this method has obvious limitations.

It is an object of my invention to provide improved means that will permit a compression test to be made on a relatively thin specimen such as a single thickness of sheet of any desired metallic or non-metallic material. A further object is to provide an improved compression specimen holder for a relatively thin sheet specimen whereby a high degree of lateral stability is obtained together with accurate and sensitive determination of the strain characteristics of the thin specimen.

A further object is to provide an improved compression specimen holder for relatively thin sheet specimens that is relatively simple and inexpensive in construction, operation and maintenance and that will permit a specimen to be inserted or removed with ease and dispatch.

Other objects and advantages will be more apparent to those skilled in the art from the following description of the accompanying drawing in which:

Fig. 1 is a perspective of my holder for making compression tests showing the specimen in position;

Fig. 2 is a sectional view of my improved holder shown in relation to the usual compression loading platens of any suitable materials testing machine;

Fig. 3 is a perspective of one guiding jaw of my improved holder; and

Fig. 4 is a fragmentary transverse sectional view showing the manner in which the specimen is centered between the guiding jaws.

In the particular embodiment of the invention disclosed herein, I have shown a frame or housing 1 of any suitable height and depth provided with a vertical recess 2 which is preferably machined starting from the front surface of the frame. A pair of bars 3 and 4 extend across the

open front face of the recess and are rigidly secured to the frame 1 by screws 5 or other suitable means. Disposed with recess 2 are a pair of vertically elongated and slideable backing blocks 6 and 7 preferably T-shaped in cross-section. These blocks are preferably slightly longer than the height of housing 1 so that they normally project above the upper surface thereof when the frame and blocks are both flush on the loading table of a testing machine. The backs of the blocks bear against the end walls of recess 2 while each of the inner ends of the T stems support a series of rollers 8 and 9. A relatively thin elongated specimen 10 is placed between the opposed sets of rollers 8 and 9 which are brought into guiding contact with the specimen by adjustment of a pair of screws 11 and 12 threaded in the end of frame 1 and preferably terminating in a vertical groove 13 in the rear surface of one of the backing blocks 6. This groove prevents accidental displacement of the backing block. The two series of rollers are specifically shown as being supported by relatively small and independent spring clips 15, the rollers having small trunnions pivotally supported in the outer ends of the clips while the inner ends of the clips are firmly held to the backing blocks by pairs of clamping strips 16 and 17 secured in position by screws. The foregoing manner of supporting the rollers in spring clips is the invention of R. L. Templin and therefore does not per se constitute a part of my invention. However, instead of clips, I have heretofore held the rollers in position by heavy grease such as vaseline and with the rollers so held in position the specimen can be inserted in the space between the rollers in the manner shown in Figs. 1 and 2.

If it is necessary to transversely center the specimen 10 two opposed upper screws 18 and 18' 40 may be threaded through strip 3 and through the back side of housing 1 to engage the specimen and bring it to its central position. A similar set of screws is also provided at the lower end of the specimen. With the thin specimen inserted in the holder in the manner shown the whole device is then placed upon a lower platen 20 of any suitable loading apparatus such as a materials testing machine whereupon a downwardly moving upper platen 21 applies a compression load 50 to the upper end of specimen 10. As the compression load is applied the specimen is free to deform in a straight vertical line in accordance with its strain characteristics. During this compression load the specimen is restrained from bending laterally by the rollers 8 and 9 bearing

against the backing blocks 6 and 7 and at the same time the rollers will insure sufficient freedom of movement of the specimen at all points along its length so that a true strain measurement can be obtained. The extent of actual deformation is relatively small and hence the rollers and their supports are adapted to allow sufficient rolling action of the rollers during a compression operation thereby avoiding any slipping of the rollers about a fixed point. It will be understood that the rollers are sufficiently spaced to insure freedom of action and yet are close enough to impart the necessary lateral stability to the specimen.

If desired, suitable strain gauges may be applied to the specimen and these may be supported upon rods such as 22 and 23 suitably mounted upon the housing 1. The spacing between the bars 3 and 4 and a similar cut-out spacing in the back of the frame 1 permits strain gauges to be brought into gauge point contact with the edges of the specimen.

From the foregoing disclosure it is seen that I have provided a very compact, simple and effective means for making a compression test of a relatively thin specimen of such length that it does not have sufficient lateral stability to permit a compression test to be made directly thereon. Also my improved device is highly accessible and durable together with a high degree of accuracy and sensitivity.

It will of course be understood that various changes in details of construction and arrangement of parts may be made by those skilled in the art without departing from the spirit of the invention as set forth in the appended claims.

I claim:

1. A device for making compression tests of a relatively thin specimen comprising, in combination, opposed rolling means whose rolling axes extend transversely of the direction of movement of the specimen, said means being spaced apart to receive and laterally engage a relatively thin specimen during application of a compression load thereto, and means for maintaining said opposed rolling means in their operative position. 45

2. A device for making compression tests of a relatively thin specimen comprising, in combination, a frame, a pair of vertically extending backing members supported by said frame in spaced relation to each other so as to receive a relatively thin specimen and laterally support the same during application of a compression load thereto, and rollers extending transversely of the direction of movement of the specimen, said rollers being interposed between each side of the specimen and said backing members to allow relatively free strain deformation of the specimen.

3. The combination set forth in claim 2 further characterized in that said backing members are substantially T-shaped in cross-section with the base of the T supported against the frame and the stems of the T's being directed toward the specimen.

4. The combination set forth in claim 2 further characterized by the provision of means for varying the spacing between the backing members so as to accommodate specimens of different thickness.

5. The combination set forth in claim 2 further characterized by the provision of means for transversely centering the specimen.

6. A device for making compression tests of a relatively thin specimen comprising, in combination, a frame having a vertical recess that is accessible from its upper and lower ends and its sides, a pair of backing blocks vertically movable in said recess and normally spaced apart to receive a compression specimen, and rotatable anti-friction means whose rotatable axes extend transversely of the direction of movement of the specimen, said rotatable means being interposed between each side of said specimen and the adjacent ends of said blocks thereby to allow strain deformation of the specimen during compression loading thereof while laterally stabilizing the specimen.

WILEY P. MONTGOMERY.
